FREDERICK HENRY ROYCE, OF WEST WITTERING, NEAR CHICHESTER, ENGLAND, AS
SIGNOR TO ROLLS ROYCE LIMITED, OF DERBY, ENGLAND

SHOCK ABSORBER DEVICE

Application filed June 24, 1927, Serial No. 201,183, and in Great Britain June 24, 1926.

This invention relates to shock absorbers and more particularly to hydraulic shock absorbers, in which a piston divides a cylinder into two compression chambers, with 5 spring controlled by-passes for the contained liquid.

The chief object of the invention is to provide means by which small movements of the springs of a vehicle are resisted only slightly, while during flexing of greater amplitude the resistance builds up rapidly, reaching a maximum value, then continues constant through any further flexing of the springs.

Another object is to provide for this action in both directions of movement, but with greater resistance to movement in one direction than in the other.

Another object is to provide a mechanism which will operate in these two desirable 20 ways, almost independently of changes of viscosity of the contained liquid, due to changes of season and temperature.

Other objects will be seen in the structure, as described below and shown in the accompanying two sheets of drawings, in which

Fig. 1 is a vertical, longitudinal section on the line 1—1 of Fig. 2.

Fig. 2 is a horizontal, longitudinal section of same, with some parts in top view.

Fig. 3 shows in section the end d_4 of the piston with its by-pass slots e_6 , the piston valve e_1 being seen in end view in the direction of arrow 3 in Fig. 2; and

Fig. 4 is a vertical transverse section on line 4—4 of Fig. 1.

The same reference characters refer to corresponding parts in the different figures.

The body casting a comprises the cylinder a_0 ; the chamber a_1 above the cylinder; the 40 rocker arm housing a_2 in communication with chamber a_1 ; the laterally extending boss a_3 , Fig. 4 providing a bearing for the rocker shaft b ; the reservoir a_4 , Fig. 4, in communication with chamber a_1 and extending

45 down one side of the casting to communicate with passage a_9 , Fig. 1, by means of holes a_{14} and a_{15} in the hollow plug a_7 , Figs. 1 and 4. The cap a_5 secured to the end of the structure and cap a_6 secured over the 50 rocker arm housing form a closed system to

be filled with a liquid, preferably oil. The only break of the closed system is due to shaft b , which connects with lever b_1 on the outside. Leakage through the bearing of shaft b is prevented by a suitable packing gland in housing b_2 , Fig. 4.

Lever b_1 is to be connected by suitable means to an axle of a vehicle, while the body casting a is mounted on some part of the vehicle body, to oppose resistance to movements of the axle in the manner described below.

The inner end of shaft b is squared, as at b_5 , Fig. 1, and has rocker arm b_6 clamped to it by bolt b_7 . The rocker arm depends through opening a_{13} in the cylinder wall and opening a_{16} in the piston wall and is connected by link b_8 to knuckle b_9 , which is mounted in the head d_1 of piston d . By means of this train, any relative movement of vehicle body and axle will move piston d in cylinder a_0 .

In addition to head d_1 , the piston has a diaphragm d_2 . The piston then divides the cylinder into two compression chambers at 75 its two ends and if the head and diaphragm were solid and the system filled with oil, the piston would be prevented from moving. The objects of the invention, stated above, are attained by valve controlled ports 80 formed in the piston, through which the two compression chambers communicate.

As seen in Figures 2 and 4, ports e_{13} are formed in suitable bosses in the piston casting and connect the compression chamber beyond head d_1 on the left with that beyond diaphragm d_2 on the right, while preventing communication of either chamber with the open central part of the piston and the rocker arm housing. But oil is not free to flow from one chamber to the other. A piston valve e_1 is interposed, which allows oil to pass from one chamber to the other under predetermined conditions and pressures.

Near the end d_4 of the piston, its wall has a thickened section which is bored to receive the close fitting piston valve e_1 . The bore is broken into three faces by the two annular grooves e_{12} and valve e_1 is shown registering with the middle face, being normally held in

this position by the two opposed springs *e4* and *e11*.

Spring *e4* bears against valve *e1* and against spacer ring *e3* mounted on diaphragm *d2* and so tends to move valve *e1* to the right. It is seen in Figure 1 that valve *e1* has a small diameter cylindrical guide *e2* extending to the left into the bore of guide rim *d3*, which is formed on diaphragm *d2*, to keep valve *e1* in perfect alignment.

Within guide *e2* the spring *e11* surrounds stud *e5*, which is mounted on diaphragm *d2*, the spring bearing against nut *e8* at one end and against spacer ring *e9* in the guide at its other end and so tends to move valve *e1* to the left, against spring *e4*. The two springs are made of such length and spacer rings *e3* and *e9* are chosen of such thickness as to hold valve *e1* in the position shown, registering with the middle face of the piston bore.

The middle face is an unbroken ring, closely fitting valve *e1*. Each of the other or extreme faces has a plurality of slots *e6* and *e7*, Figures 1 and 3, cut across it to form a by-pass for oil when the valve moves a predetermined distance from normal position. The grooves *e12* are for facilitating the machining out of slots *e6* and *e7*.

It will be understood then that movement of the piston can occur in either direction, without passage of oil from one compression chamber to the other, so long as the movements are small, due to ordinary unevenness in a good road, leaving the vehicle springs free to flex. In these small movements of the piston to right and left, valve *e1* moves to left and right, relative to the piston, sliding in the middle face of the bore, springs *e4* and *e11* yielding easily.

But if the movement is greater than this small amount, the resistance of springs *e4* and *e11* becomes a retarding factor. Consider movement of piston *d* in one direction, say to the right. As the movement continues, valve *e1* is forced to the left relative to the piston. When the movement has gone far enough to carry valve *e1* off the middle face of the bore, oil can pass from the right compression chamber through slots *e7* and ports *e13* to the left compression chamber.

During this movement of valve *e1* the resistance of spring *e4* rapidly builds up, retarding the movement of the piston and hence the flexing of the vehicle spring. But the increasing resistance does not continue beyond a predetermined degree, it reaches a maximum beyond which it cannot go. For when slots *e7* open, oil can pass and valve *e1* moves no farther against the resistance of spring *e4*. As the movement of the piston continues, oil escapes at substantially constant pressure; the flexing of the vehicle spring can continue, but with a constant, not an increasing, retarding force.

Movement of the piston to the left brings

spring *e9* into action in the same manner, resisting the movement with a rapidly increasing force, which reaches a maximum and then retards further flexing of the vehicle spring, in the opposite direction, with a constant retarding force.

But spring *e4* is seen to be a stouter spring than *e11*, so that while the retarding action is alike in both directions, rapidly building up to a maximum and then continuing substantially constant, this maximum is greater in one direction than in the other. The retarding force in either direction may be determined, as desired, by a spring of suitable strength.

It is well known that changes of temperature cause great variations in the viscosity of oil. But variations in viscosity of the oil can cause only slight changes in the operation of this device, for valve *e1* simply opens a little wider when the viscosity increases, the increased compression of springs *e4* and *e11* from this cause being negligible.

At the top of each compression chamber is a passage *b3* leading to chamber *a1* and controlled by wall valve *b4*. Screw *b10* limits the ball to very slight lifting off its seat, so that in the operation of the device only negligible volumes of oil can pass, but any air in the cylinder can quickly escape.

At the bottom of each compression chamber is a similar passage *a11* leading into passage *a9* and controlled by ball valve *a12*. Screw *a10* limits the ball to slight lifting so that only small volumes of oil can pass, but these are sufficient to insure that the compression chambers shall be always completely full of oil. Oil in small volumes then passes the upper ball *b4* at each increase of pressure in its compression chamber and passes the lower ball *a12* at each fall of pressure.

This slight circulation passes from the compression chambers through chamber *a1*, down through reservoir *a4*, through holes *a14* and *a15* and passage *a9*, back to the compression chambers. A fine gauze *a8* may be soldered over holes *a14* to arrest any foreign matter. Plug *a7* may be unscrewed and removed for cleaning the gauze.

By this means, flexing of the vehicle springs by ordinary unevenness of the road is left substantially unmodified; while compressive and recoil flexing due to large inequalities in the road is greatly modified. Compressive flexing is retarded by rapidly increasing resistance, which reaches a maximum and then continues constant. But the resistance to compressive flexing may be relatively small. Recoil reflexing also is opposed by a rapidly increasing resistance, which reaches a maximum and then continues constant, but this maximum is much greater than with the compressive flexing. The inequalities of the road are smoothed out to a greater degree by this improved shock ab-

sorber. And its operation remains automatically unchanged by changes of season and temperature.

While I have described a preferred form 5 of the device, the invention is not intended to be limited to the form shown and described.

What I claim is:—

1. A hydraulic shock absorber comprising 10 a closed cylinder, a hollow piston having one end open, a compression chamber on each side of the piston, a diaphragm in the piston forming a chamber adjacent its open end, a conduit through the piston connecting the chamber within the same to the compression chamber remote therefrom, valve mechanism 15 controlling the passage of liquid through the chamber within the piston adapted to open on pressure in either direction, and two springs, one reacting to restrain the opening 20 of the valve in one direction and the other reacting to restrain the opening in the other direction, so that during a predetermined initial amount of movement of the piston from normal position, the valve shall remain 25 closed.

2. A hydraulic shock absorber comprising 30 a closed cylinder, a hollow double-ended piston therein, a compression chamber on each side of the piston, means for operably connecting the "shocked" member to be restrained to the piston, a diaphragm across the interior of the piston forming a chamber at one end thereof, an opening through the end of the piston connecting the chamber 35 within the same to the adjacent compression chamber and admitting the flow of liquid from one chamber to the other, conduits through the body of the piston connecting the chamber within the same to the compression chamber remote therefrom and admitting passage of liquid between such two chambers, a piston valve fitting and slidable in the interior of the chamber within the piston, passage ways adapted to enable fluid to 40 pass from one side to the other of the piston valve when the valve is moved from normal position, two springs, one reacting to restrain the piston valve from moving on pressure in one direction and the other reacting to restrain the piston valve from moving on pressure in the other direction.

3. A hydraulic shock absorber comprising 45 a closed cylinder, a hollow double-ended piston therein, a compression chamber on each side of the piston, means for operably connecting the "shocked" member to be restrained with the piston, a diaphragm across the piston forming a chamber at one end thereof, an opening through the end of the piston connecting the chamber within the same to the adjacent compression chamber, and admitting the passage of fluid from one chamber to the other, conduits through the body of the piston connecting the chamber 50 within the same to the compression chamber

remote therefrom and admitting passage of liquid between such two chambers, a part of the wall of the chamber within the piston thickened on the inner side, such part extending round the circumference and for a suitable axial length, a piston valve fitting and sliding in such "thickened wall" part and normally located across the centre of such part, axial grooves in the thickened wall part on either side of the normal location of the piston valve whereby on movement of the piston valve away from its normal position liquid can pass from one side to the other of the piston valve, two springs one re-acting 70 to restrain the piston valve from moving under pressure in one direction and the other reacting to restrain the piston valve from moving under pressure in the other direction.

4. A hydraulic shock absorber comprising 75 a closed cylinder, a hollow double-ended piston therein, a compression chamber on each side of the piston, means for operably connecting the "shocked" member to be restrained with the piston, a diaphragm extending across the piston forming a chamber 80 at one end thereof, a co-axial cylindrical projection extended from the diaphragm into the chamber within the piston, a hole through the end of the piston connecting the chamber within the same to the adjacent compression chamber and admitting passage of liquid between such chambers, holes through the body of the piston connecting the space between the cylindrical projection and the wall of the chamber within the piston to the compression chamber remote therefrom and admitting the passage of liquid between such space and compression chamber, a part of the wall of the chamber within the piston thickened on the inner side, such part extending round the circumference and for a suitable axial length, a two diameter piston valve, the smaller part fitting and sliding in the said cylindrical projection and the larger part fitting and sliding in the "thickened wall" part and normally located across the centre thereof a hole through the centre of the piston valve, a pin rigidly secured to the centre of the diaphragm protruding through the said hole, with a substantial clearance therefrom, of suitable length with a shoulder near its free end the part beyond the shoulder threaded, a washer or seating threaded on to such pin abutting against the shoulder and a nut screwed on to the thread to secure the same, two coil springs one encircling the cylindrical projection and reacting between the diaphragm and the larger part of the piston valve and the other encircling the pin and reacting between the seating or washer and the piston valve, radial recesses in "thickened wall" part extending the whole length thereof except the part of the normal location of the piston valve whereby on movement of the piston in either 90 95 100 105 110 115 120 125 130

direction from normal position liquid can pass from one side to the other of the piston valve.

5. A hydraulic shock absorber comprising a closed cylinder, a piston, a compression chamber on each side of the piston, a passage connecting the two compression chambers through the piston, valve mechanism controlling the passage opening on pressure from either side, elastic means restraining the opening of the valve, a reservoir, a conduit from the bottom of such reservoir to each of the compression chambers, and a one way valve controlling each of such conduits.
13. A hydraulic shock absorber comprising a closed cylinder, a piston, a compression chamber on each side of the piston, a passage connecting the two compression chambers through the piston, valve mechanism controlling the passage opening on pressure from either side, elastic means restraining the opening of the valve, and air leaks permitting the escape of air from the compression chambers.
21. A hydraulic shock absorber comprising a cylinder closed at both ends; a hollow piston in the cylinder; a valve seat formed by a thickened portion of the piston wall, having a finished bore broken by two annular grooves into three faces; a piston valve slidably fitting the bore; by-passes formed by slots across the two extreme faces; and springs adapted to hold the piston valve in register with the middle face to close the by-passes.

In witness whereof I have signed this specification.

FREDERICK HENRY ROYCE.
